ATTORNEYS

UNITED STATES PATENT OFFICE.

THOMAS JAMES IRWIN, OF TRENTON, NEW JERSEY.

TOY.

1,218,405.

Specification of Letters Patent.

Patented Mar. 6, 1917.

Application filed May 2, 1916. Serial No. 94,895.

To all whom it may concern:

Be it known that I, THOMAS J. IRWIN, a citizen of the United States, and a resident of Trenton, in the county of Mercer and State of New Jersey, have invented a new and Improved Toy, of which the following is a full, clear, and exact description.

This invention relates to the construction of toys, and more particularly to a toy of that type in which sand or equivalent granular material feeds into a car to cause the latter to move by gravity from a receiving to a discharging position.

The invention has for its general objects to provide a novel toy which is capable of easy erection or dismantling by and to the amusement of children, the toy embodying in its design a pair of oppositely acting cars or receptacles adapted to be alternately filled, whereby the filled car descends to a position where it automatically discharges its load, but in descending it raises the other car to receiving or filling position.

An additional object of the invention is the provision of a hopper and chutes so arranged as to alternately fill the cars, there being valves which are automatically opened by the ascending cars, and there also being adjustable spouts whereby the flow of material can be automatically cut off when the weight of the material in the car is sufficient to overbalance the empty car and raise the latter, and thus by adjusting the spouts the toy can be used for heavy or light granular material with equal facility.

The invention has as an additional object a novel arrangement of means for automatically returning the material after being discharged by the cars to the hopper, so that the toy or machine will continuously operate as long as the power is supplied.

With such objects in view, and others which will appear as the description proceeds, the invention comprises various novel features of construction and arrangement of parts which will be set forth with particularity in the following description and claims appended hereto.

In the accompanying drawings, which illustrate one embodiment of the invention and wherein similar characters of reference

indicate corresponding parts in all the views,

Figure 1 is a side view of the toy with portions in section;

55

Fig. 2 is an end view thereof;

Fig. 3 is a horizontal sectional view on the line 3—3, Fig. 1;

Fig. 4 is a detail sectional view on the line 4—4, Fig. 1;

60

Fig. 5 is a fragmentary sectional view of the hopper; and

Fig. 6 is an enlarged sectional view of one of the buckets.

Referring to the drawing, A designates the base of the apparatus, B the frame, C the hopper and chute construction, D the cars and E the conveying mechanism for returning the material to the hopper.

The parts of the toy are so designed that they can be readily taken apart for packing into a small space, and in this regard the toy is of the construction type for exercising the ingenuity of the child in putting the toy together and taking it apart.

75

The base A comprises a frame 1 on the top of which is fastened a horizontal bed-plate 2. On this plate the superstructure of the toy is supported. Rising from the ends of the plate 2 are short posts 3 securely fastened in place which serve to detachably anchor the frame B on the base A. The center of the bed plate 2 has a transverse trough 4 into which the sand or other granular material is discharged by the cars or carriers D.

80

The frame B is composed of sections of tubular stock detachably fastened together, and embodies at opposite sides a pair of uprights 5 which have their lower ends fitted over the posts 3 and their upper ends receive connecting lugs or studs 6 fastened to the ends of a pair of horizontal, spaced bars 7, which latter are connected by transverse connectors 8. By lifting the upper bars or rods 7, the connecting studs 6 are raised out of the standards 5, and then the latter can be lifted off the base so as to completely take down the frame.

95

The construction C comprises a central hopper 9 having oppositely inclined chutes 10 which are fastened to vertical plates 11

which are portions of angle brackets 12 detachably secured to the rods 7 by means of bolts 13 which pass through the horizontal plates 14 and the rods 7. The plates 12 serve as stoppers for holding the material in the chutes and each plate 11 has an opening 15 controlled by a cut-off valve 16, the latter being pivoted at 17, as shown in Fig. 2, and having an arm 18 which carries a weight 19 for yieldingly holding the valve in closed position. The lower end of each chute has an opening 20 in its upper side which is closed by a slide valve 21 that can be opened to clear out the chute if it should become clogged. The horizontal member 14 of each bracket 12 has a spout 22 provided with a vertically adjustable section 23, whereby the discharge end of the spout can be raised or lowered to thereby control the amount of material that is fed into a car or holder D, according to the weight of the material which will constitute a charge. This spout 22 is located between the standards 5 so as to enter the car D, which is open at the top. The cars D slide between the standards 5 and have shoes 24 for slidably engaging the standards. Each car is provided with a cross-bar 25 in which engage hooks 26 on the ends of cables 27. These cables extend over guide pulleys 28 carried by shafts 29 on the upper ends of the standards, and the cables extend from one side of the machine to the other and suspend the cars so that when one car moves upwardly the other moves downwardly. Each car is a box-like receptacle having a sloping bottom 30 and a discharge opening 31 in the side toward which the bottom slopes, and this opening 31 is closed by a pivoted valve 32 which has a weight-carrying arm 33 to hold the valve closed. Each car carries an adjustable member 34 which extends upwardly and is adapted to engage the associated chute valve 16 so as to open the latter and cause material to flow out of the chute into the raised car. As soon as the car receives its proper amount of material it moves down by gravity, and the open valve 16 is caused to close by gravity. As the loaded car moves downwardly the valve 32 thereof is finally opened by the arm 33 of the valve striking an adjustable stop 35 carried by the standards adjacent the bottom of the frame. The material discharges from the cars down chutes 36 which incline to the trough 4 to deliver the material to the latter. These chutes 36 have hooks 37 on their upper ends for engaging a horizontal bar 38 on each pair of standards 5. Since the cars are attached to the cables by hooks, the cars can readily be detached.

The material can be returned from the trough 4 by hand through the use of a scoop or similar device, or, if desired, an endless conveyer may be used for this purpose. In

the drawings, this endless conveyer E comprises a chain 39 which has a plurality of spaced buckets 40, the lower end of the chain being guided around a sprocket wheel 41 disposed in the trough 4 and the upper end 70 guided around a sprocket wheel 42 carried by standards 43 above the hopper 9. The buckets in descending enter the top and take up some of the loose material, and as the loaded buckets descend they finally empty 75 their contents into the hopper. The endless conveyer is operated in any suitable manner, as, for instance, by an electric motor 44 on the base A, and which is controlled by a switch 45, the motor being operatively connected through suitable transmission with the shaft 46, on which is the sprocket 41 for the endless chain 39. In taking the toy apart of course the chain is detached from its sprocket as a preliminary step. When 80 the parts of the toy are put together it forms a comparatively rigid structure and can be moved about from place to place with safety.

From the foregoing description taken in connection with the accompanying drawing, 90 the advantages of the construction and method of operation will be readily understood by those skilled in the art to which the invention appertains, and while I have described the principle of operation, together with the apparatus which I now consider to be the best embodiment thereof, I desire to have it understood that the apparatus shown is merely illustrative and that such changes may be made when desired as 95 fall within the scope of the appended claims.

Having thus described my invention I claim as new and desire to secure by Letters Patent:

1. A toy of the class described comprising 105 a supporting structure, a central hopper disposed at the upper part thereof, a well, an endless conveyer discharging material from the well to the hopper, oppositely moving cars connected together, means controlled by each car, whereby a load is delivered from the hopper to one car at a time, so that the descending car elevates the other car, and means for delivering the load of a descended car to the said well. 110

2. A toy of the class described comprising 115 a supporting structure, a central hopper, chutes connected therewith and extending in opposite directions, valves normally closing the chutes, a car movable up and down in line with the lower end of each chute, means on the car for opening the valves, valves on the cars, means in the path of the cars for opening the valves thereof when the cars move downwardly to a predetermined position, means for delivering the contents of the cars to a common point, and means for delivering the material from such common point to the said hopper. 120

3. A toy of the class described compris- 130

- ing a supporting structure, a central hopper, a well under the hopper, outwardly diverging chutes connected with the hopper, cars movably mounted on the said structure vertically in line with the lower ends of the chute, valves controlled by the cars for supplying material from the chutes to the cars, means for connecting the cars together to move alternately, downwardly-
5 converging chutes for directing material to the said well, means for discharging the material from the cars to the last-mentioned chutes, and means for transferring material from the well to the said hopper.
- 10 4. A toy of the class described including a chute, an adjustable spout at the lower end thereof, an open-top car movable vertically to and from the chute, a valve actuated by the car for controlling the discharge of material from the chute to the spout, and means for movably mounting the car.
- 15 5. A toy of the class described comprising a base, a frame supported thereon, vertically movable cars guided on the frame, means for connecting the cars together, whereby a filled car descends and causes the other car to ascend, a hopper device removably mounted on the top of the frame, at 20 the center and between the cars, adjustable spouts at the discharge portions of the hopper device and adapted to extend into the cars when in their uppermost position, and valves controlling the flow of material from 25 the hopper device.
6. A toy of the class described comprising a base, a frame supported thereon, vertically movable cars guided on the frame, means for connecting the cars together, whereby a filled car descends and causes the other car to ascend, a hopper device removably mounted on the top of the frame, adjustable spouts at the discharge portions
